UNITED STATES PATENT OFFICE.

CHARLES S. HUBER, OF SHELBY, OHIO.

MANIFOLDING BOOK.

Application filed September 7, 1922. Serial No. 586,604.

This invention relates to manifolding devices and with respect to its more specific features to manifolding books such as salesbooks and the like.

One of the objects of the invention is the provision of a manifolding salesbook whereby three or more copies may be made at one writing by the utilization of two or more pads equipped with special means for holding one of the books in place.

Another object is the provision of a practical device for holding one of the pads in proper position for manipulation of its leaves into and out of superposed relation to those of another pad, and to practically assure that the first mentioned pad shall assume correct operative position.

Other objects will be in part obvious and in part pointed out hereinafter.

The invention accordingly consists in the features of construction, combinations of elements and arrangement of parts which will be exemplified in the construction hereinafter set forth, and the scope of their application will appear in the appended claims.

In the accompanying drawing forming part of this specification wherein similar reference characters refer to similar parts throughout the several views,

Figure 1 is a perspective view of a manifolding device embodying the invention;

Fig. 2 is a detail perspective view of the pad holding jaws with associated support;

Fig. 3 is a sectional view of a locking device for the jaws;

Fig. 4 is a sectional view showing another detail; and

Fig. 5 is a diagrammatic view of a pad.

Referring now more specifically to the drawing the numerals 1, 2 and 3 indicate three sections of a backing, the sections 2 and 3 being hinged at the sides 4 and the sections 1 and 2 being connected by the flexible cloth hinge material 5. The backing sections may be composed of stiff material, such as pasteboard or metal, and the hinges may be provided by the covering material for the sections, as cloth, which may be extended for the purpose. The numeral 6 indicates a spring clamp carried by the backing section 3 and adapted to grip and hold the pad 7 on the backing. The pad 7 is composed of a plurality of superposed sets of original and duplicate leaves, the numeral 8 indicating an original leaf and the nu-

meral 9 a duplicate leaf of one of the sets, these two leaves being provided from a single sheet folded and weakened along the line 10. The duplicate leaf 9 may be longer than the original leaf 8, the extended portions of the duplicate leaves of each set being bound together by staples 11 to form a pad. The numeral 12 indicates a weakened line in each duplicate leaf this weakening facilitating separation of the duplicate leaf from the stub.

At one side of the pad 7 is a standard adapted to support one or more record sheets in position to be manipulated into and out of superposed relation with the leaves of the pad 7. In the embodiment illustrated this clamp includes a pair of relatively movable clamping jaws 13 and 14, these jaws upstanding from the backing section 2, the jaw 13 being fastened to the backing section 2 through the instrumentality of an integral flange 15 riveted to the backing as at 16.

The numerals 17 indicate the leaves of a supplemental book or pad, these leaves being preferably of tissue paper. The supplemental pad may be formed by providing a pile of tissue leaves (Fig. 5) and stitching them through the center, as at 40, to attach them together. Thereupon the leaves of the pile may be folded along the stitched line 85 to provide a book of tissue leaves. If desired, and as is preferable, a sheet of paper 41 more durable than tissue may be associated with the outside of the backing and attached thereto by the stitching to provide a cover for the tissue book. One of the leaves of this cover is interposed between the jaws 13 and 14 of the standard, and passes beneath the inner jaw 14 so as to lie smoothly on the upper face of the backing section 2.

Having placed the leaf of the pad 17 between the jaws 13 and 14, these jaws may be closed to hold the pad of tissue leaves in position on the standard and in proper relation to the pad 7. In operative position the line of stitching closely follows the upper edge of the jaw 13, so that the central portion of the tissue pad is elevated above the backing section 2, to a plane upon nearly approximately the upper face of the pad 7.

The jaw 14 is pivoted for movement toward and from the jaw 13 in a plane parallel to the plane of the pad and in the present embodiment is pivotally connected to the

latter jaw at 18. At the ends of the jaws remote from the hinge 18 means to retain the jaws in closed relation are provided. The numeral 19 indicates a keeper, being a flat plate moving closely alongside the inner face of the jaw 13 into and out of position overlapping the end of the jaw 14, when the latter is in closed position. The advance end of the keeper may be beveled 10 to facilitate the assumption of overlapping relation to the jaw 14. The numeral 20 indicates a pin or screw longitudinally translatable on the jaw 13 and having threaded engagement with the keeper 19. In the 15 present embodiment the screw 20 extends through a slot 21 in the jaw 13 and into engagement with the keeper 19. The screw 20 has a manipulative head on one side of the jaw 13, the keeper 19 being disposed at 20 the opposite side of the jaw 13.

The pivoted jaw 14 is wide at its bottom where it is adapted to rest upon the cover leaf 41. The wide bottom not only provides a substantial area of the lower face of jaw 25 14 co-operative with the flange 15 to grip the cover leaf, but in a large measure restrains the jaw from sinking into the surface of the cover leaf or any other one or more underlying leaves. In the present embodiment the wide bottom is provided by 30 the angularly projecting flange 22 of the jaw 14 which flange extends in a direction away from the jaw 13. On the inner face of jaw 14 are one or more projections, or sheet holding 35 devices, as the pins 23, which may be provided by punching the jaw so as to upset its inner face to produce the pins. In the inner face of the jaw 13 are recesses with which the pins 23 are adapted to register. 40 In the embodiment illustrated the recesses are provided by the apertures 24 in the jaw 13.

In setting the instrument, the jaw 14 is 45 opened and the tissue pad applied to rest on the upper edge of the jaw 13, with the line of stitches closely adjacent to and following said edge, and with the cover leaf 41 extending downwardly alongside the inner face of jaw 13 and onto the face of the 50 backing section 2. It is then in correct position. The jaw 14 may readily be closed when only the cover leaf lies on the section 2, whereas, should the body of the tissue pad, or an abnormal number of sheets thereof, lie 55 on the section 2 with the line of stitches at the lower edge of the jaw 13, the jaw 14, when in or near its closed position, would be displaced relative to jaw 13 and slant upwardly due to the greater thickness of 60 the underlying body which is made up of a great number of tissue leaves, and on or over which the flange 22 would lie. If the lower edge of the jaw 14 were narrow this jaw might be pressed and moved down so as 65 to sink into the body and thus assume its

normal clamping position relative to the jaw 13. The tissue pad, so clamped, would be in an awkward if not practically impossible position for practical manipulation of its leaves to interleaved relation with those 70 of the other pad 7. Hence the wide feature of the jaw 14, as referred to, renders the application of the tissue pad under the jaws both awkward and noticeable, with the result that the operator will be practically 75 obliged to set it in the correct position mentioned. Having placed the tissue pad and its leaf 41 in proper position, the jaw 14 is rotated to closed position in which the flanges 15 and 22 are closely superposed. 80 Then the finger of the operator is placed on the screw head 30 which latter is circular and has a knurled periphery and the head is drawn toward the axis 18 and at the same time rotated by a wiping action of the finger. By this operation the keeper will be longitudinally moved, or translated, into overlapping relation to the jaw 14 and continued rotation of the head will press the two jaws toward each other and firmly 85 secure them in closed relation. By the reverse operation the keeper 19 may be moved out of overlapping relation with jaw 14 and the jaws freed for being opened.

It will be noted that the sheet 41 which 90 is held between the jaws, also lies beneath the flange 22 of the pivoted jaw and by its cooperation with upper face of the backing section 2 or with the flange 15 assist in holding the supplemental pad in place. 100

Having clamped the tissue pad in place, one of the tissue leaves is placed between the leaves 8 and 9 of the uppermost set of the pad 7, so as to lie on the transfer leaf 31, one end of which latter may be bound 105 with the pad 7 by the staples 11. The transfer leaf may be coated on each face with the transfer material. The original leaf 8 will lie on the interposed tissue leaf 17. Inscription made on the original leaf will 110 appear on the duplicate leaf and on the tissue, or triplicate leaf. By rotating the backing section 3 on the hinge side 4 as an axis, the inscribed tissue leaf will be withdrawn from between leaves 8 and 9 and 115 will fall on backing section 2, where it will be held when the backing section 2 is restored to place. The leaf 9 may be torn from the stub along the line 12, and the leaves 8 and 9 torn apart along line 10, 120 and disproved of as desired.

By supporting the tissue pad on the standard or jaw 13 in elevated position above the face of the backing section 3, a width of tissue leaf may be employed which will lie 125 in stored relation beneath the section 2 without crumpling and which will lie on the pad 7 without objectionable projecting from the right hand margin of the pad 7, referring to Fig. 1. 130

Thus by the above described construction are accomplished among others the objects hereinbefore referred to.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention what I claim as new and desire to secure by Letters Patent is:—

1. In a device of the character described, in combination, a backing adapted to support a pad, a standard mounted on said backing adapted to support one or more sheets in position to be manipulated into and out of superposed relation with said pad, said standard including a pair of relatively movable clamping jaws alongside the position of said pad, said jaws being connected so as to restrict their relative movement, and means adapted to retain said jaws in closed relation, one of said jaws having means adapted to cooperate to displace it upwardly relative to the other jaw when an abnormal number of sheets lie therebeneath with the jaws in closed relation.

2. In a device of the character described, in combination, a backing adapted to support a pad, a standard mounted on said backing adapted to support one or more sheets in position to be manipulated into and out of superposed relation with said pad, said standard including a pair of pivotally connected clamping jaws alongside the position of said pad, one of said jaws being stationary and the other movable in a plane parallel to the plane of said pad, the latter jaw having, at its bottom, a wide flange extending in a direction away from the other jaw, and means adapted to retain said jaws in closed relation.

3. In a device of the character described, in combination, a backing adapted to support a pad, a standard mounted on said backing adapted to support one or more sheets in position to be manipulated into and out of superposed relation with said pad, said standard including a pair of pivotally connected clamping jaws alongside the position of said pad, a keeper movable rela-

tive to one of said jaws and into and out of overlapping relation with the other when the jaws are in closed relation, and a keeper 65 actuating device including a screw longitudinally translatable on one of said jaws, passing therethrough and having threaded engagement with said keeper.

4. In a device of the character described, 70 in combination, a backing adapted to support a pad, a standard mounted on said backing adapted to support one or more sheets in position to be manipulated into and out of superposed relation with said pad, said standard including a pair of pivotally connected clamping jaws alongside the position of said pad, one of said jaws being stationary and the other movable in a plane crosswise of the position of said pad, the latter jaw having, at its bottom, a wide flange extending in a direction away from the other jaw, means adapted to retain and release said jaws from closed relation including a screw passing through said stationary jaw and longitudinally translatable thereon, and a keeper mounted on said screw and longitudinally translatable therewith, the movable jaw having a flange adapted to underlie said keeper when the jaws are in 80 closed relation.

5. In a device of the character described, 85 in combination, a backing adapted to support a pad, a standard mounted on said backing adapted to support one or more sheets in position to be manipulated into and out of superposed relation with said pad, said standard including a pair of pivotally connected clamping jaws alongside the position of said pad, one of said jaws being 90 stationary and the other movable in a plane crosswise of the position of said pad, the latter jaw having, at its bottom, a wide flange extending in a direction away from the other jaw, one of said jaws having one 95 or more sheet holding pins projecting from its inner face, and means adapted to retain said jaws in closed relation.

6. In a device of the character described, 100 a standard including a pair of clamping jaws pivotally connected together at one end, each of said jaws having a flange, said flanges adapted to lie in close superposed relation when the jaws are in closed relation, one of said jaws having one or more sheet holding pins projecting from its inner 105 face, a screw passing through and longitudinally translatable on one of said jaws, a keeper threaded on said screw and translatable therewith longitudinally of the latter jaw, said screw having a manipulative head 110 on the side of the jaw opposite said keeper.

In testimony whereof I affix my signature.
CHARLES S. HUBER.
